GAME

Sverre Quisling, Madison, Wis.

Application June 15, 1933, Serial No. 675,991

2 Claims. (Cl. 273—141)

This invention relates to an exciting game of chance and skill.

It may be applied to advertising,—confection boxes, or booklets as desired to enhance their value so people will keep them for long periods of time.

The construction of the device embodied by the invention and the method of using same will be more clearly understood from the following detailed description and accompanying drawing in which:

Figure 1 is a perspective view of a device made in accordance with the invention and

Figure 2 is a detailed sectional view showing method of mounting bat-pointer mechanism of the device.

Referring to the drawing a confection box or similar article 1 is shown having upon one face the figure or reproduction of a baseball player 2. This figure is shown in batting position and pivoted to the box at a position adjacent to the hands of the player is a pointer in the form of a baseball bat 3. This bat 3 is pivoted to the box by means of a fairly snug fitting eyelet 4 carrying a small spacer 5 interposed between the pointer or bat 4 and the box. The head of the eyelet is turned over to clamp the pointer fairly tight against the spacer 5 thus setting up friction which prevents pointer from having more than limited movement when snapped by the finger of the player. The bat is divided into an upper segment 6 which is snapped by the player's finger causing it to move forward and the lower segment 7 being in the form of a pointer will also move. Upon the face of the box below the pivot of the bat are a series of numbers 8, each number lying within a marked field, said fields being relatively spaced in order to provide spaces for no score areas for pointer 7. The bat is so mounted that the edge of the ma-

terial upon which it is mounted prevents the player carrying his snapped finger beyond a certain distance which prevents cheating.

The game is to be played by 2 players. One player sets the bat in any desired position. The other player then strikes the bat using a snapping motion of his finger. This causes the indicator to move to numbers or to blank spaces between numbers which blank counts 0.

A predetermined number may be considered game score or the game is played for total score after a certain number of trials.

This description does not wish to limit the game to any exact size or form, but includes all changes in detail which fall within the scope of the claims which follow.

I claim:

1. In a game of chance and skill, a pointer frictionally pivoted near one end with its longer end extending beyond the material on which it is mounted, said friction being sufficient to limit rotation so that skill as determined by tactile impact of finger to said pointer can be measured by numerical score recorded on a playing field on which said pointer rotates.

2. In a game of chance and skill a playing field, an elongated pointer adapted to be struck by a player's finger and connected near one of its ends to a support having thereon a playing field, by means of a frictional pivot, said pivot having sufficient friction to limit the rotation of the pointer to less than one revolution, said pointer having its longer end extending slightly beyond the edge of said support on which it is mounted so it may be followed only a limited distance by the finger in playing field, a series of numbers, each in a marked field upon the playing field spaced relative to one another with which the pointer co-acts to tally the score.

SVERRE QUISLING. 40
